TELEGRAPHY

Herbert Muth, Berlin, Germany, assignor to Tele-funken Gesellschaft für Drahtlose Telegraphie m. b. H., Berlin, Germany, a corporation of Germany

Application June 2, 1937, Serial No. 145,953
In Germany February 1, 1936

2 Claims. (Cl. 178—66)

This invention relates to a transmitter arrangement for the production and transmission of brief impulses.

This invention is concerned with the production of brief radio frequency impulses, especially the kind used for measuring distances and for direction finding work.

The keying of radio frequency transmitters at the rate and rhythm of the desired impulses may be effected either in the control or master stage itself or in one of the following amplifier stages. The keying of self-oscillatory tubes, however, involves the drawback that the length, amplitude and the form of the impulses are a function to a marked degree of the prevailing regeneration conditions of the tube and that therefore the feedback can not be altered without causing an incidental effect upon the said characteristics of the impulses. In the case of keying master-excited stages in which, for instance, by the blocking and unblocking of the amplifier tubes brief impulses are produced, one difficulty arises in the attempt to neutralize the amplifier stages. As a result of neutralizing defects of the keyed stages, as will be seen, radio frequency oscillations are liable, during the keying intervals (spacing periods), to flow from the master or pilot stage into the aerial, with the result that waves would be sent out also during spacing periods.

Now, according to this invention the shortcoming residing in the two keying methods hereinbefore mentioned is obviated by that an intermediate frequency obtained by the mixing of two different frequencies is transmitted at the impulse rhythm.

An exemplified embodiment of the invention shall be described in what follows by reference to the accompanying drawing wherein Figures 1 and 2 show two embodiments of my means for producing short impulses.

Suppose the self-oscillatory tube 1 comprising the oscillatory circuit $L_1 C_1$ produces wave energy of a frequency f_1 , while tube 2 with oscillation circuit $L_2 C_2$ produces a frequency f_2 . The ensuing two waves are modulated or beat in tube 3 with the result that in the oscillatory circuit $L_3 C_3$ wave energy of a frequency equal to either the sum or the difference of f_1 and f_2 is filtered out and fed directly into the antenna 12 or by way of an additional stage 18 as in Figure 2, to the antenna 12.

If, then, by way of the choke coil D the grid of the tube 3 is blocked for the alternating potentials of the generators 1 and 2, the mixing process

in 3 will be discontinued and as a consequence of insufficient neutralization of tube 3, which may be neutralized as shown in dotted lines, the aerial will radiate only the frequency f_1 or frequency f_2 to which, however, the receiver apparatus will not respond.

The circuit organization here disclosed makes it possible in the simplest possible way to dispense with the keying of a self-oscillatory tube regardless of difficulties of neutralization in master operated stages.

It will be understood that the mixer tube may be followed by additional amplifier stages designed for the sum or the difference of the two constituent frequencies f_1 and f_2 as shown in Figure 2, and these, if necessary, for complete suppression of antenna radiation during the spacing periods could be keyed as shown simultaneously with the mixer tube.

For the purpose of stabilization of the transmitted radio frequency energy it will also be readily possible to stabilize the two tubes 1 and 2 by ways and means well known in the prior art, say, by the aid of monitor quartz crystals.

If the mixer tube is of the twin-grid type, then merely one grid need to be subjected to keying action.

I claim:

1. In means for producing high frequency impulses of short and substantially uniform duration, a plurality of sources of high frequency wave energy, a utilization circuit, an electron discharge tube amplifier having input and output electrodes, means coupling said input electrodes to said sources of high frequency wave energy whereby said high frequency wave energies are impressed thereon to be beat against each other therein, circuit means, tuned to respond only to a frequency resulting from said beating action, coupled to said output electrodes and to said utilization circuit whereby waves of said frequency resulting from said beating action only reach said utilization circuit, and means including a key and a source of potential connected with the electrodes of said tube to key said tube on and off whereby high frequency wave impulses of short and substantially constant duration are transferred by said output circuit to said utilization circuit.

2. In means for producing high frequency impulses of short and substantially uniform duration, a pair of sources of high frequency wave energy, a utilization circuit, a plurality of electron discharge tube amplifiers each having input and output electrodes, means coupling the input

electrodes of one of said amplifiers to said high frequency sources whereby said high frequency wave energies are impressed thereon to be beat against each other in said one tube, circuit means, tuned to respond only to a frequency resulting from said beating action, coupling the output electrodes of said one tube to the input electrodes of the other tube, means coupling the output electrodes of said other tube to said utili-

zation circuit, whereby waves of said frequency resulting from said beating action only are transferred by said tubes to said utilization circuit, and means for keying said tubes on and off whereby high frequency wave impulses of short and substantially constant duration are impressed on said utilization circuit. 5

HERBERT MUTH.
